UNITED STATES PATENT OFFICE

93,837

DESIGN FOR A KITCHEN CABINET

Emmett G. McQuinn, New Castle, Ind., assignor to Hoosier Manufacturing Company, New Castle, Ind., a corporation

Application July 2, 1934, Serial No. 52,581

Term of patent 7 years

To all whom it may concern:

Be it known that EMMETT G. MCQUINN, a citizen of the United States, residing at New Castle, in the county of Henry and State of Indiana, has invented a new, original, and ornamental Design for a Kitchen Cabinet, of which the following is a specification.

Reference is made to the accompanying drawings wherein

Fig. 1 is a front perspective view of a kitchen cabinet, showing my new design, and

Fig. 2, a similar view with the cabinet in the opened condition.

I claim:

The ornamental design for a kitchen cabinet, as shown and described.

In testimony whereof I affix my signature.

EMMETT G. MCQUINN.
